SHIP'S HULL

Reginald Paulsen, Oslo, Norway

Application January 7, 1937, Serial No. 119,372
In Norway July 29, 1936

2 Claims. (Cl. 114—79)

The present invention relates to improvements in ship-hulls and it has for its object to provide a reinforcing structure for the walls of the ship such as shells, decks, bulk heads, tank tops, etc. 5 whereby it will be possible to build such walls from lighter material than heretofore and thus reduce the weight of the hull accordingly.

According to the invention I attain this object by providing a framing structure or truss which 10 is secured to the parts to be reinforced and constructed and arranged to take up not only a substantial portion of the pressure exerted against the hull wall but also the longitudinal stresses occurring therein.

15 The invention is illustrated in the accompanying drawing which shows, by way of example, several preferred embodiments of reinforcing structures and wherein Fig. 1 is a vertical elevation showing schematically the reinforcing structure. Fig. 2 is a similar view of a modified arrangement. Fig. 3 is a sectional view on line A—A of Fig. 1. Fig. 4 is a sectional view on line C—C of Fig. 2. Fig. 5 is a sectional view on line B—B of Fig. 2. Fig. 6 is a schematical view of a 20 series of longitudinal sections as applied to the hull of a ship.

Similar numerals refer to similar parts throughout the several views.

The reinforcing structure according to my invention 30 comprises a main strut 1 or a securely interlocked series of such struts extending in a longitudinal direction in regard to the hull, and a number of rigidly interconnected stiffening elements or struts 2, the whole being constructed and arranged so that the various stresses to which 35 the ship may be exposed shall be distributed over the entire length of the hull.

The main strut 1 is fastened at certain intervals to the plates of the hull and its intermediate portions are bent to extend at a distance therefrom. The stiffening struts 2 are arranged 40 to form diagonal braces between the main strut 1 and the wall of the hull, as clearly shown in Fig. 4. The stiffening struts 2 are connected to the 45 wall of the hull and strut 1 respectively by any suitable means such as by welding or riveting.

The compression strains acting upon the bulk-

heads 6 are taken up by plates or girders 3 which are suitably fastened to the wall and extend at right angles therefrom. Additional struts 4 are provided by means of which a permanent connection may be established between the main structure and said girders or plates. I preferably attain this by either providing holes in said plates or girders through which the auxiliary struts 4 may pass.

I claim:

1. A reinforcing wall structure for use in ship hulls comprising continuous longitudinal main struts extending lengthwise to the walls of the hull, said struts being fastened to the walls at certain intervals and having their intermediate 15 portions formed to extend at a distance from the face of said walls, diagonal struts inserted between said main strut and the wall of the hull and connected to the main strut and the wall of the hull to firmly maintain the respective 20 relationship between said walls and struts, a plate at each extremity of the individual main struts fastened to the wall of the hull and extending at right angles therefrom, openings in said plate, and additional struts passing through said open- 25 ings and connected at their free ends to the main strut.

2. A reinforcing wall structure for use in ship hulls comprising continuous longitudinal main struts extending lengthwise to the walls of the 30 hull, said struts being fastened to the walls at certain intervals and having their intermediate portions formed to extend at a distance from the face of said walls, diagonal struts inserted between said main strut and the wall of the hull 35 and connected to the main strut and wall of the hull to firmly maintain the respective relationship between said walls and struts, a girder at each extremity of the individual main struts fastened to the wall of the hull and extending at right angles therefrom, a cover plate fixed to the free end of said girder, and additional struts connected with their free ends to said cover plate and the main struts.

REGINALD PAULSEN.
